Primary Examiner — Philip S Hyder(74) *Attorney, Agent, or Firm* — Cozen O'Connor(57) **CLAIM**

The ornamental design of a utility knife, as shown and described.

DESCRIPTION

FIG. 1 is a front perspective view of a utility knife showing a new design;

FIG. 2 is a top view thereof;

FIG. 3 is a back view thereof;

FIG. 4 is a front view thereof;

FIG. 5 is a bottom view thereof;

FIG. 6 is left view thereof; and,

FIG. 7 is a right view thereof.

The shade lines in the figures show contour and not surface ornamentation.
